UNITED STATES PATENT OFFICE

EUGENE S. VANDER MARK, OF SPRINGMONT, PENNSYLVANIA, ASSIGNOR TO READING SHEET METAL PRODUCTS CO., OF READING, PENNSYLVANIA, A CORPORATION OF PENNSYLVANIA

WINDOW VENTILATOR AND SCREEN

Application filed August 1, 1927. Serial No. 209,688.

This invention relates to improvements in combined window ventilators and screens and more particularly to a novel window ventilator and screen which is adjustable to accommodate windows of various sizes.

One of the objects of the invention is to provide a combined device of this character in which the screen has extensible or adjustable ends to accommodate windows of different sizes and for use in attaching the device to a window, and in which a panel with a series of louvered openings is vertically slidable on the screen frame and is removable from the latter by lifting the panel upwardly.

Another object of the invention is to furnish such a device with novel means for engaging the ends of the screen with the parting bead of a window frame, the parts being so constructed that the sash may be raised and lowered in front of the device, this making it unnecessary to remove the device when the sash is to be raised or lowered.

25 A further object is to provide a combined ventilator and screen which may be readily secured to the top of the upper sash of a window by suitable fastening means, so that the room may be ventilated from above if desired.

30 A further object is to furnish a device of this type in which the screen during the winter may be covered by a panel with ventilating louvers formed therein; said panel being removable to leave only the screen mesh for summer use.

35 A still further object is to provide novel means for securing the wire mesh to the frame of the screen.

40 With the foregoing objects outlined and with other objects in view which will appear as the description proceeds, the invention consists in the novel features herein-after described in detail, illustrated in the accompanying drawing and more particularly pointed out in the appended claims.

Referring to the drawing:

Fig. 1 is a front view of the lower portion of a window frame with the improved

ventilator and screen mounted therein, the louvered panel being shown partly raised.

Fig. 2 is a horizontal sectional view taken on line 2—2 of Fig. 1.

Fig. 3 is a vertical sectional view taken 55 on line 3—3 of Fig. 1.

Fig. 4 is a vertical sectional view of certain details of the screen and illustrating the manner of attaching the wire mesh to the frame.

Fig. 5 is a similar view of the same parts 60 after the wire mesh has been secured in position.

Fig. 6 is a perspective view of one corner of the screen and portions of the louvered 65 panel and one of the adjustable extensions.

In the drawings, 1 designates a window frame provided with the usual grooves 2 and 3 separated by the parting strip or bead 4. The sash 5 slides in the grooves. 70

The device forming the subject matter of the invention may be arranged at either the upper or lower end of the window frame. The device includes a screen 7 having adjustable end plates 8, and a louvered panel 9 cooperates with the screen. The screen consists of a rectangular frame divided vertically by a strip 10, and the screen frame, as shown in Fig. 4, is made of a sheet metal stamping having a channel-shaped part 75 11, a flange 12, a grooved portion 13 and a locking flange 14.

In assembling the screen, the wire mesh 15 is stretched across the frame with its end portions over the channel-shaped part 11, 85 and then a clamping frame 16, which is substantially C-shaped in cross section, is placed against the rear side of the wire mesh and forced into the channel-shaped part 11. In this operation the part 17 of the clamping frame forces a portion of the wire mesh against the inclined part 18 of the screen frame, and the turned edge 19 of the clamping frame presses an adjacent portion of the wire mesh against the channel-shaped part 11.

After the parts are pressed into place, the locking flange 14 is pressed into the position shown in Fig. 5 where it overlaps the clamping frame and prevents the latter 100

from detaching itself from the screen frame.

The grooves 13 formed in the top and bottom rails of the screen frame act as guides for hooks or flanges 20 arranged at the top and bottom edges of adjustable ends

5 8. Each of these end plates is preferably made of a piece of sheet metal, suitably bent to provide the hooks 20, and as these hooks engage the grooves, the end plates may readily slide toward and away from each other. The outer extremity of each end

10 plate is cut away to provide tongues 21 and ears 22, the tongues being relatively thin so that they may be inserted into the

15 sash grooves between the screen and the parting bead. The ears 22 abut against the parting bead to limit the outward movement of the sliding extensions 8 of the screen, and as shown in Fig. 3, each ear has a slot 23 to receive the headed end of a screw or the like which may be employed in fastening the ears to the parting bead.

20 Of course, if the device is mounted at the top of the window frame, such headed fastenings will hold the device at the top of the frame.

25 The ears 22 also function as stops for the sliding extensions to prevent the latter from moving inwardly past the ends of the screen frame.

30 The grooves 13 at the sides of the screen frame receive hooked guide portions 24 of the side edges of the panel 9, and this construction permits the panel to be removed by simply raising the panel above the screen frame. To facilitate this, the upper edge of the panel may be provided with a rearwardly extending flange 25 which normally rests on top of the screen frame, and which may be readily grasped by the operator when the panel is to be removed.

35 The panel is also preferably made of a sheet metal stamping and is provided with louver openings 26 which admit the air and exclude drafts, rain and snow.

40 In manufacturing the device, the various parts with the exception of the wire mesh, may be made of sheet metal stampings and the screen frame and clamping frame may 50 each consist of a number of strips connected at their ends by spot-welding or the like.

45 From the foregoing it will be seen that the invention provides an adjustable combination window ventilator and screen which may be made of durable steel with an oven baked enamel finish. The mesh forming part of the device may be of copper and will be sufficiently fine to exclude 55 mosquitoes and other objectional insects.

60 What is claimed and desired to be secured by Letters Patent is:

1. A combination window ventilator and screen comprising a frame carrying wire mesh, adjustable extensions for the ends of

the frame, slideable laterally towards and away from each other, and a louver panel adjustably mounted on the screen frame and slidably upwardly and downwardly thereon.

2. In a device of the character described, 70 a screen frame carrying wire mesh, adjustable extensions for the frame arranged on one face of the frame and movable on the latter towards and away from each other, and a louver panel movably mounted on 75 the screen frame, arranged on the opposite face thereof and movable in a path at right angles to the path of movement of the adjustable extensions.

3. In combination, a screen frame carrying 80 wire mesh and provided at its top, bottom and ends with guide ways, adjustable extensions for the frame having guide members sliding in the guide ways at the top and bottom of the frame, and a louver panel 85 having guide members engaging the guide ways at the ends of the frame to permit the panel to be slid upwardly and downwardly over said wire mesh.

4. An extension for a window ventilator 90 frame comprising a sheet metal plate provided at its top and bottom edges with guide members, one end of said extension having upper and lower tongues to engage a sash groove of a window frame, and an 95 ear integral with the plate and arranged at an angle to said tongues, said ear having a slot to receive a fastening device used in securing the ear to a window frame.

100 In testimony whereof I affix my signature. EUGENE S. VANDE MARK.
